RAIL LEVELER

Filed July 8, 1944

UNITED STATES PATENT OFFICE

2,434,254

RAIL LEVELER

Dale A. Benner, Alton, Ill.

Application July 8, 1944, Serial No. 544,015

1 Claim. (Cl. 153—38)

1

This invention relates to rail levelers; and it has special reference to mechanisms or tools for removing from a car rail a distortion or deformation commonly and popularly known and designated as a "dish" or a "hog" which has been imparted to the rail during and as an incident to its use, and distorting or deforming it into a sunken rail.

Objects of the invention are to provide an improved portable metallic frame of unyielding form and strength in order to resist and withstand the severe and sometimes excessive strains and stresses to which it may be subjected when used, composed of a minimum amount of material and of minimum weight, and having its structural elements and its operative parts in novel cooperative assembly and formation; to provide an angular or generally inverted U-shaped rugged metallic frame having integral rail receiving abutments on its ends, and a tubular socket within and integral with the frame midway between its said ends for enclosing the major portion of a screwthreaded shaft which is movable longitudinally as required to remove the dish or hog from a sunken rail engaged in said abutments; to provide pivotally connected vise jaws swiveled on the lower end of said shaft for gripping or engaging under the rail head on opposite sides of the web of the rail; and to provide operative mechanism in the frame for positively moving said shaft longitudinally and thereby leveling or straightening the sunken rail and removing the distorted or deformed dish or hog therefrom.

Another object of the invention is to provide an improved portable metallic rail leveler having integral abutments for receiving and engaging spaced portions of a metallic distorted or deformed sunken rail, a shaft mounted in said frame for longitudinal movements in directions approximately at right angles to said sunken rail engaged in said abutments, and vise jaw members swiveled on the end portion of said shaft that is toward said rail for positively engaging and modifying a sunken rail into its original shape and form in order to level and remove any dish or hog from said rail, and mechanism mounted in and cooperating with said frame for positively moving said shaft longitudinally as aforesaid when said mechanism is rotated about said shaft.

Other objects and advantages of my improved rail leveler should be apparent from the following description, reference being made to the annexed drawing, in which—

2

Fig. 1 is an elevation showing one side of my improved rail leveler and the mechanism supported thereby for positively moving the rail leveling shaft longitudinally.

Fig. 2 is an elevation showing the opposite side of my improved rail leveler and the shaft operating mechanism.

Fig. 3 is an enlarged vertical sectional view approximately on the line 3—3 of Figs. 1 and 2, showing the operating mechanism in one operational position.

Fig. 4 is a similarly enlarged vertical sectional view of the operating mechanism in another position.

Fig. 5 is a like enlarged horizontal sectional view of the operating mechanism on the line 5—5 of Fig. 2.

Fig. 6 is an end elevation showing one of the rail receiving abutments which are integral with the respective ends of the rigid frame.

In the form of the invention shown, the portable metallic frame is of great strength and of very strong and unyielding form in order to resist and withstand any excessive and severe strains and stresses when used. It is composed of a minimum amount of metal and is of minimum weight, and of novel form to provide maximum strength. For the attainment of these objectives, the body of said frame is formed with an outer angular or bowed tension member 1, a complementary inner angular or bowed compression member 2, and downwardly diverging arms 3 integral with the ends of said tension and compression members, respectively; a web 4 midway between the side edges of and integrally uniting and holding said tension and compression members rigidly spaced apart and having a central opening 5 midway of its ends and approximately midway between said tension and compression members; side frame portions 6 extending along opposite sides of the opening 5 and laterally from both sides of said web 4, from integral connection with the tension member 1 to integral connection with the compression member 2; annular walls 7 and 8 at the outer and inner sides of the opening 5 integrally connecting said side frame portions 6 and constituting thrust supports for shaft moving mechanism hereinafter described; axially aligned tubular sockets or bored bosses 9 and 10 between and integrally connecting the tension member 1 with the annular wall 7 and the compression member 2 with the annular wall 8, respectively, as clearly shown in Fig. 3; abutment walls 11 for the head of a sunken rail, said walls extending along

the ends of the web 4 and integrally connecting the adjacent ends of the tension member 1 and compression member 2; webs 12 integrally connected with the extensions 3 and the undersides of the respective abutment walls 11; and open handles 13 attached to and diverging upwardly and laterally from the central portion of the tension member 1. This entire frame is preferably composed of a single casting, with the exception that the handles 13 may, if desired, be welded or otherwise attached to the frame after the frame and handles have been separately formed.

The abutment spaces 14 are longitudinally aligned on the ends of the frame and are designed and intended to receive spaced portions of a sunken rail 15 and to hold the same substantially immovable during operation of the mechanism for leveling or removing the dish or hog therefrom. These abutments constitute means for centering or locating the sunken rails properly in position for engagement of the leveling mechanism with said rails. Said mechanism comprises a screwthreaded shaft 16 extending into the tubes 9 and 10 midway between the abutments 11—3 on the respective ends of the frame and approximately at right angles to any sunken rail 15 mounted in said abutments.

The mechanism shown in Figs. 3, 4 and 5 for moving the shaft 16 longitudinally in opposite directions comprises a ratchet nut 17 located in the opening 5 and screwed on said shaft 16. Said nut may be mounted either in the position shown in Fig. 3, or in the position shown in Fig. 4. In Fig. 3 the inner end of the nut 17 is seated and rotative against the outer end of the tube 10 and the outer side of the annular wall 8. A ring 18 has a radial flange 19 extended inwardly from its inner end and seating directly against the outer end of the nut 17 and encircling an outwardly extended tubular portion 20 of the nut. The wall of the opening through the nut 17 and the tubular extension 20 thereof are formed with screw threads screwed on the threaded shaft 16. A ring 21 having approximately the same internal diameter as the ring 18 abuts against the outer end of said ring and has a radial outer end wall 22 abutting against the inner end of the tube 9 and against the annular wall 7. A roller anti-friction bearing device 23 of known construction is located within the rings 18 and 21 and between the walls 19 and 22 of said respective rings. It is easily understandable that the relative positions of the nut 17 and the anti-friction bearing device may be reversed and arranged in the positions shown in Fig. 4; that is, that the nut 17 may be mounted in the opening 5 with its end abutting against the annular wall 7, the tubular part 20 extending toward the annular wall 8 and having the anti-friction bearing device mounted thereon. This arrangement involves a reversal of the nut and the anti-friction bearing device from the position shown in Fig. 3 to the position shown in Fig. 4, and will be readily understood by those familiar with such devices.

In either the arrangement shown in Fig. 3 or the arrangement shown in Fig. 4, the ring 18 is directly attached to the ratchet nut 17 by a number of fastener pins 24 extending through holes in the flange 19 of said ring and engaging in holes in the adjacent end of the nut 17, leaving the ring 21—22 free to remain stationary or to rotate with the ring 18—19 when the nut 17 is rotated.

From the foregoing it is evident that the nut 17 may be rotated to move the shaft 16 to proper longitudinal position for subsequent functional operation by manually rotating the ring 18 which constitutes a handle or hand wheel for such purpose. And the nut 17 may be positively rotated for functional purposes by the ratchet mechanism shown comprising a ring 25 encircling the ratchet nut 17 for oscillating turning movements about and with said nut. Said ring 25 supports a reversible ratchet device 26 engageable with the peripheral teeth 27 on the nut in order to turn said nut forcibly in either direction. The ring 25 is formed with an integral socket 28 to receive an end of an operating lever or bar for positively turning the operating mechanism in either direction and thereby move the shaft 16 longitudinally in one direction or the other, as desired. Said ratchet mechanism has the same general construction and mode of operation as disclosed in my prior Patent No. 2,261,949, November 11, 1941. The ratchet ring 25 is prevented from longitudinal displacement along the nut 17 by engagement with an adjacent part of the frame and with the ring 18, between which said ratchet ring is located after this mechanism has been assembled in the frame.

Two pivotally connected vise jaws are swiveled on the lower end of the shaft 16 for gripping or 30 engaging under the head of the rail 15 on opposite sides of the web of said rail. The vise jaw 29 has a lateral extension 30 intermediate of its ends engaged between a pair of spaced extensions 31 projecting from the complementary vise 35 jaw 32. A pin 33 pivotally attaches the extensions 30 and 31 and is spaced equidistant from the inner sides of the jaws 29 and 32. Arms 34 project inwardly from the upper ends of the vise jaws 29 and 32, respectively, and have upwardly inclined inner walls seating upon and around a complementarily inclined or upwardly tapered head 35 integral with the lower end of the shaft 16. That is, the shaft 16 extends between the arms 34 of the vise jaws 29 and 32, and the head 35 engages under and forms swivel connection with said arms.

The lower ends of the vise jaws 29 and 32 have integral inwardly extended projections 36. This provides a device acting and functioning as a vise supported by swivel connection with the shaft 16 in a relationship in which the pivot 33 operatively connecting the two vise jaws 29 and 32 is below the lower end of the shaft 16 and below the head 35, and in which the rail engaging projections 36 are spaced below the extensions 30 and 31 far enough to permit the head of the rail 15 to be received between said projections 36 and said extensions. It is evident that the shaft may be moved to a longitudinal position in which the rail 15 may be moved longitudinally to engage the head of said rail above the projections 36, in which position said projections 36 engage under the rail head and at opposite sides of the web of said rail, as shown. Then the shaft 16 may be moved longitudinally and upwardly through the frame of the device by the operating mechanism which has screwthreaded engagement with said shaft. Upward movement of the shaft 16 causes the upwardly tapered head 35 to engage 50 against the inclined inner walls of the arms 34 and thereby spread apart the upper ends of the vise jaws 29 and 32, causing the projections 36 on the lower ends of said vise jaws to grip between them the rail web and rigidly engage under the rail head. Further and continued up-

ward longitudinal movement of the shaft 16 by forcible operation of the operating mechanism therefor levels the rail and removes therefrom the distortion or deformation herein described as a dish or a hog, and which had been imparted to the rail during and as an incident to its use, or otherwise. In this operation, the rail is engaged by the abutment devices 3-11 on opposite ends of the rigid frame, and is thereby held from displacement. During operative use of the device, rotation of the shaft 16 is substantially prevented by a pin 37 rigid with the head 35 and projecting between the jaws 29 and 32.

It is now evident that the frame of my improved portable metallic rail leveler comprises the minimum amount of metal required to form an unyielding frame of the necessary strength. The structural elements and parts of said frame are arranged in a novel cooperative relationship in order to resist and withstand the relatively great and severe pressures, strains and stresses to which the device is subjected when in use, without deformation, and to provide for use of said minimum amount of metal. It is also evident that this invention attains all of its intended objects and purposes efficiently, economically and satisfactorily, and possesses many advantages over other devices intended for these uses. I contemplate such variations as may be necessary to adapt the invention for any use desired without departure from the scope of the appended claim.

I claim:

A rail leveler having an arcuate frame with bifurcated ends arranged and adapted to fit upon the top of a rail, two axially aligned tubular bosses, integral with the frame midway of its ends and spaced from each other thereby providing an intervening space, a screw shaft jour-

nalled in and extending through the bosses, a nut threaded on the shaft between said bosses in said intervening space, a circular head on the lower end of the screw shaft, a pair of jaw members pivoted together as levers of the first class with their upper ends engaging about said circular head thereby providing a swivel connection between the shaft and the jaw members and the bottom ends of the jaw members, arranged and adapted to engage the underside of the rail, and means for rotating said nut, whereby upon rotating the nut the screw shaft and with it the jaw members will be raised to lift that portion of the rail engaged by the jaw members relative to the portions engaged by the ends of the frame.
